UNITED STATES PATENT OFFICE.

WILLIAM J. MILLER, OF LOGANSPORT, INDIANA.

BRAKE MEANS FOR RAILWAY-CARS AND THE LIKE.

1,158,706.

Specification of Letters Patent.

Patented Nov. 2, 1915.

Application filed December 4, 1914. Serial No. 875,451.

To all whom it may concern:

Be it known that I, WILLIAM J. MILLER, a citizen of the United States, residing at Logansport, in the county of Cass and State of Indiana, have invented certain new and useful Improvements in Brake Means for Railway-Cars and the like, of which the following is a specification.

My invention relates to improvements in 10 brake-means for railway cars and the like.

An important object of the invention is to provide means of the above-mentioned character, which may be thrown into action by the brakeman or attendant without excessive 15 exertion upon his part, and without exposing him to undue danger or accidents.

A further object of the invention is to provide brake-means of the above-mentioned character, which is operated by a wheel or 20 wheels of the car after being manually actuated.

A further object of the invention is to provide means of the above-mentioned character, which is simple in construction, durable, relatively inexpensive to manufacture, 25 convenient in use, and reliable in operation.

Other objects and advantages of this invention will be apparent through the course of the following description.

In the accompanying drawings forming a 30 part of this specification and in which like numerals are employed to designate like parts throughout the same, Figure 1 is a side elevation of apparatus embodying my invention. Fig. 2 is a horizontal sectional view taken on line 2—2 of Fig. 1, Fig. 3 is an end elevation of the apparatus. Fig. 4 is a vertical transverse sectional view taken on line 4—4 of Fig. 1. Fig. 5 is a similar view 35 taken on line 5—5 of Fig. 1, and Fig. 6 is a perspective view of brake-locking means.

In the drawings, wherein for the purpose 40 of illustration is shown a preferred embodiment of my invention, the numeral 10 designates the body of a car, shown for the purpose of illustration as an ordinary box-car. Arranged below and near the ends of the body 10 are truck-frames 11 and 12, carrying flanged wheels 13. These trucks are pivotally connected with the body 10, in any well known or preferred manner. The numerals 14, 15 and 16 designate longitudinal beams, embodied in the car-body 10, as shown.

55 The trucks 11 and 12 are equipped with brake mechanism of any well known or pre-

ferred type. This brake mechanism comprises brake-shoes 17 disposed for engagement with the flanged wheels 13. These brake-shoes are carried by transverse brake-beams 18, pivotally connected with hangers 19, as shown. Disposed near each inner brake-beam 18 is a vertically inclined lever 20, pivotally connected between its end as shown at 21, with a bracket 22, rigidly mounted upon the adjacent inner brake-beam. The lower end of the vertically inclined lever 20 is pivotally connected with a longitudinally extending link 23, extending below the brake-beams 18, as shown. The 70 opposite end of the longitudinally extending link 23 is pivotally connected as shown at 24, with the lower end of a vertically inclined swinging lever 25, having pivotal connection between its ends, as shown at 26, 75 with a bracket 27, rigidly attached to the outer brake-beam 18. At the upper end, this vertically inclined lever is pivoted, as shown at 28 with a bracket 29, rigidly secured to a portion of the truck-frame. 80

From the foregoing description, it is obvious that when the upper end of each of the vertically inclined levers 20 is swung inwardly, the two sets of brake-shoes will be moved into clamping engagement with the 85 flanged wheels, to stop the car.

The numeral 30 designates a horizontal swinging lever having its inner end pivoted to the longitudinal beam 15, as shown at 31. The opposite end of the lever 30 has pivotal 90 connection with a link, cable, or other non-extensible connecting element 32, having pivotal connection with the end of the adjacent inclined lever 20, as shown.

The numeral 33 designates a second horizontal swinging lever, pivoted between its ends as shown at 34, to the longitudinal beam 16, as shown. Pivotally connected with one end of the lever 33 is a link, cable, or other non-extensible connecting element 100 35, having pivotal connection with the adjacent inclined lever 20.

The numeral 36 designates a common operating lever pivoted between its ends, as shown at 37, to the longitudinal beam 16. A 105 link or like element 38 pivotally connects the lever 36 with the lever 30 while a link or like element 39 pivotally connects the lever 36 with the lever 33.

Rigidly connected with the longitudinal 110 beam 16 is a laterally extending horizontal bearing or bracket 40, receiving a stud-shaft

41, which carries a worm wheel 42, as shown. This worm wheel carries a spool or grooved pulley 43 arranged upon the outer side thereof and rigidly secured thereto. Pivotally secured to the normal upper side of the grooved pulley or spool 43 is a chain or other flexible element 44, having connection with one end of the lever 36. It is obvious that upon the rotation of the spool 43 in either direction from the normal position, the flexible element 44 will be wound thereon, and the lever 36 swung to apply the brakes.

Extending longitudinally upon the outer side of the longitudinal beam 16 is a rotatable longitudinal movable driving shaft 45, extending through brackets or bearings 46 and 47, as shown. This driving shaft is provided with a worm 48 engaging the worm wheel 42, as shown. Disposed upon opposite sides of the bearing 46 and surrounding the end portion of the longitudinal driving shaft 45 are stiff coil-springs 49 engaging the bearing and stop-sleeves 50 rigidly secured to the operating shaft 45. The function of these coil springs is to normally prevent the longitudinal movement of the driving shaft 45, in either direction, but to permit the longitudinal movement of the same in either direction, when its rotation is opposed beyond a predetermined degree, as will be more fully described.

Means are provided to positively lock the driving shaft 45 against rotation, when the same moves longitudinally in either direction. Such means comprises a tapered rotatable brake-member 51, rigidly secured to the shaft 45, and decreasing in diameter toward its opposite ends. Disposed inwardly of and in engagement with the rotatable brake-member 51 is a brake-shoe 52, having an outer longitudinally curved or concaved surface, receiving and engaging with the brake-member 51 as shown. The brake-shoe 52 is pivotally connected with a bracket 53, rigidly secured to the longitudinal beam 16, by a vertical pin 54 as shown. Stiff coil-springs 55 are arranged upon opposite sides of the vertical pivot 54 and engage the opposite ends of the shoe 52 to normally retain the same in the transverse position at a right angle to the longitudinal beam 16. When the operating shaft 45 is in the normal longitudinal position, before being moved longitudinally in either direction, the tapered brake-member 51 is arranged centrally within the concaved surface of the brake-shoe 52, and while engaging therewith the same permits of the rotation of the operating shaft 45. However, upon the longitudinal movement of the operating shaft 45 in either direction, the brake member 51 is moved longitudinally with respect to the shoe 52, which is yieldingly retained in the normal position at a

right angle to longitudinal beam 16, whereby the binding or clamping engagement between the elements 51 and 52 is substantially increased with the result that the operating shaft 45 is securely held against further rotation in either direction.

Means are provided to release the brake-member 51 from the shoe 52, when the former is being held against rotation by the latter. The operating shaft 45 extends through the bracket or bearing 47 as above stated, and is journaled within an elongated slot formed therein, whereby the shaft 45 is adapted to partake of perceptible lateral movements away from the brake-shoe 52. Pivoted upon the operating shaft 45 is a shifting cam 55, carrying an upwardly extending lever 56, as shown. At the lower end of this cam is provided a depending extension secured to which is a heavy retractile coil spring 58, attached to the longitudinal beam 16. The extension or lever 56 engages a lug 59 secured upon the bracket 47 whereby the outward swinging movement of the same is positively limited. It is thus seen that the spring 58 normally serves to hold the operating shaft 45 against lateral outward movement. Secured to the inner end or base of the bracket 47 is a cam-track 57 rigidly attached thereto and adapted to be engaged by the cam 55 when the cam and lever 56 are swung inwardly, by means to be described, whereby the operating shaft 45 is shifted laterally and outwardly, and the brake-member 51 moves out of locked engagement with the shoe 52 and the shaft 45 is left free to rotate to release the brakes.

Having a universal connection with the shaft 45, as shown at 59, is a laterally shiftable shaft 60, carrying a friction member 61, which is tapered and decreases in diameter toward its opposite ends as shown. The friction member 61 is arranged inwardly of and near the flange 62 carried by one of the wheels 13, as shown. When the longitudinally movable shaft 45 is in the normal longitudinal position, the largest portion or crest of the friction pulley 61 engages the crest of the annular flange 62, said annular flange embodying oppositely arranged inclined faces 63. The shaft 60 is adapted to be laterally shifted in a substantially horizontal plane and is journaled through an elongated opening 64 in a transversely movable bearing 65, operating within a stationary laterally extending guide 66, which is rigidly attached to the longitudinal beam 16. When the friction member 61 is moved laterally and outwardly to engage with the flange 62, the shaft 60 is rotated, which rotation is imparted to the shaft 45, whereby the brakes will be applied.

Manually operated means are provided to swing the friction member 61 into engagement with the flange 62 and to swing the

brake-pulley 52 out of engagement with the brakeshoe 52, the same comprising a longitudinal rock-shaft 65', journaled to bearings 66, as shown. As more clearly shown in Fig. 3, this rock shaft 65' is provided at its outer end with a laterally extending crank 67 having pivotal connection with an upstanding link 67'. The link 67' has pivotal connection with a vertically swinging manually operated lever 68 arranged a convenient distance above the floor extension 55' of the body portion 10 of the car. The lever 68 is pivoted to the body portion 10 of the car, as shown at 69. Pivotaly connected with the same end of the body portion 10 of the car, adjacent the top thereof, as shown at 70, is a manually operated vertically swinging lever 71, having pivotal connection with a depending link 72, which in turn is pivotally connected with the link 67'. It is obvious that by swinging either of the levers 68 and 71, upon their pivot, the rock shaft 65' may be turned, for a purpose to be next described. The rock shaft 65' is provided near and spaced from its inner end with a depending crank-portion 73, adapted to engage with the shaft 60 adjacent and upon opposite sides of the friction-member 61, to shift the shaft 60 laterally and outwardly. The crank-portion 73 is swung laterally and outwardly to bring member 61 into frictional engagement with the flange 62, when either lever 68 or 71 is swung downwardly. At its extreme inner end, the rock shaft 65' is provided with a crank 74 arranged outwardly of and near the lever 56, to engage therewith and swing the same inwardly to release the brake pulley 51 when either of the levers 68 and 71 are swung upwardly.

The operation of the apparatus is as follows:—When the car is moving and it is desired to apply the brakes to stop the same, the brakeman or attendant swings either of the levers 68 and 71 downwardly whereby rock shaft 65 is turned, the crank 73 swung outwardly, and the friction-member 61 moved into frictional engagement with the flange 62. This having been done, the rotation of the wheel 13 is imparted to the shaft 60, which accordingly rotates the shaft 45. The shaft 45 turns the worm which turns the worm-wheel 42 and the spool 43. The chain or flexible element 43 is now wound upon the spool 42 whereby the lever 36 is swung in one direction. When this lever 36 is swung, as above stated, the levers 20 are swung to apply the brakes. At first, the springs 48 are sufficiently stiff to prevent longitudinal movement of the shaft 45. When the application of the brakes increases beyond a predetermined degree, the resistance of one of the springs 48 (depending in the direction of travel of the car) is overcome, whereby the shaft 45 partakes of a slight longitudinal movement in one direc-

tion. Upon this longitudinal movement the brake member 51 has locked engagement with the brake-shoe 52, whereby when the friction member 61 engages the cam 62, the shaft 44 will be held against rotation. The shaft 45 is thus locked against rotation, until either of the levers 68 or 71 are swung upwardly, whereby rock shaft 65' is turned in an opposite direction, crank 74 swung inwardly, and the cam 55 swung for effecting an outward lateral movement of the shaft 45, moving the friction member 51 out of clamping engagement with the brakeshoe 52, and the releasing the brakes. It is obvious that the apparatus will operate with the car running in opposite directions.

It is to be understood that the form of my invention herein shown and described is to be taken as a preferred example of the same and that various changes in the shape, size and arrangement of parts may be resorted to without departing from the spirit of my invention or the scope of the subjoined claims.

Having described the invention what is claimed, is:—

1. The combination with brake mechanism of a railway vehicle, of means to operate the brake mechanism including a longitudinally movable rotatable shaft, means to rotate the shaft and means to automatically lock the shaft against rotation upon the longitudinal movement thereof in one direction.
2. The combination with brake mechanism of a railway vehicle, of means to operate the brake mechanism including a longitudinally movable rotatable shaft, means to lock the shaft against rotation upon the longitudinal movement thereof in both directions, and means to release the shaft after the same has been locked against rotation.
3. The combination with brake mechanism of a railway vehicle, of a rotatable and longitudinally movable shaft carried by the vehicle, yielding means to oppose the longitudinal movement of the shaft in one direction, driving connecting means between the shaft and the brake mechanism, means to rotate the shaft, and means to hold the shaft against rotation upon its longitudinal movement.
4. The combination with a wheeled vehicle, of brake mechanism carried thereby, means embodying a longitudinally movable shaft to operate the brake mechanism, means to automatically lock the shaft against rotation upon its longitudinal movement in one direction, and a member connected with the shaft and movable into and out of engagement with a wheel of the vehicle.
5. The combination with a wheeled vehicle, of brake mechanism carried thereby, means embodying a longitudinally movable rotatable shaft to operate the brake mech-

anism, a tapered brake member carried by the shaft to move longitudinally therewith, a brake shoe arranged in proximity to the brake member to engage therewith, and 5 means to rotate the shaft.

6. The combination with a wheeled vehicle, of brake mechanism carried thereby, means embodying a longitudinally movable rotatable shaft to operate the brake mechanism, yielding means to oppose the longitudinal movement of the shaft in one direction, a brake member carried by the shaft, a co-acting brake member arranged to engage with the first-named brake member, 10 and means to rotate the shaft.

7. The combination with a wheeled vehicle, of brake mechanism carried thereby, means embodying a longitudinally movable shaft to operate the brake mechanism, 20 springs to oppose the longitudinal movement of the shaft in both directions, a tapered brake member carried by the shaft, a co-acting brake shoe engaging the brake member, a driving shaft having universal 25 connection with the longitudinally movable shaft, a friction member carried by the driving shaft and adapted to engage with one wheel of the vehicle, and means to move the friction member into and out of engagement with the wheel.

8. The combination with a wheeled vehicle, of brake mechanism carried thereby, means embodying a longitudinally movable shaft to operate the brake mechanism, a tapered brake member carried by the shaft, a co-acting brake shoe provided with a concave face to engage with the brake member, means to pivotally support the brake shoe, 35 springs to yieldingly oppose the swinging movement of the brake shoe, means to yieldingly oppose the longitudinal movement of the shaft in either direction, and a friction member connected with the shaft and movable into and out of engagement with the 40 wheel of the vehicle.

9. The combination with a wheeled vehicle, of brake mechanism carried thereby, means embodying a worm wheel to operate the brake mechanism, a longitudinally movable 50 rotatable shaft having a worm engaging the worm wheel, means to yieldingly oppose the longitudinal movement of the shaft in either direction, means to lock the shaft against rotation upon such longitudinal movement, a member connected with the shaft and movable into engagement with a wheel of the vehicle, and manually operated means to shift the member toward and away from the wheel.

60 10. The combination with a wheeled vehicle, of brake mechanism carried thereby, means embodying a longitudinally movable

rotatable shaft to operate the brake mechanism, means to lock the shaft against rotation upon its longitudinal movement in either direction, a device to laterally shift a portion of the shaft to release the same so that it may be free to rotate, a member connected with the shaft and movable into and out of engagement with the wheel of the vehicle, and common manually operated means to operate the device and member.

11. The combination with a wheeled vehicle, of brake mechanism carried thereby, means to operate the brake mechanism embodying a rotatable member, means to lock the member against rotation, means to rotate the member, a cam pivoted upon the member, a stationary cam track to engage with the cam, a spring connected with the cam to move the same in one direction, and manually operated means to move the cam in an opposite direction in opposition to the spring.

12. The combination with a wheeled vehicle, of brake mechanism carried thereby, driving means for the brake mechanism embodying a member movable into and out of engagement with the wheel of the vehicle, means to move the member into and out of engagement with the wheel of the vehicle, and means to automatically hold the driving means against movement upon the brakes being set at a predetermined pressure.

95 13. The combination with a wheeled vehicle, of brake mechanism carried thereby, driving means for the brake mechanism, a driving shaft pivoted to the driving means, a laterally extending guide secured to the vehicle, a bearing mounted to move within the guide and receiving the driving shaft therein, a member carried by the driving shaft to engage and disengage a wheel of the vehicle, and a rock shaft having a crank 100 to engage the driving shaft and laterally shift the same.

14. The combination with brake mechanism of a vehicle, of a rotatable and longitudinally movable element carried by the vehicle, yielding means to oppose the longitudinal movement of the element in one direction, driving connecting means between the element and the brake mechanism, means to rotate the element, means to hold the element against rotation upon its longitudinal movement, and separate means to release the element whereby it is free to rotate.

110 In testimony whereof I affix my signature in presence of two witnesses.
